INDUCTIVE HEAT TREATING APPARATUS

Howard E. Soines, Grosse Pointe Park, Mich.

Application October 25, 1938, Serial No. 236,872

2 Claims. (Cl. 219--13)

The present invention relates in general to high frequency inductive heating apparatus and in particular to a method of and means for preventing disruptive discharge at undesirable points in the apparatus and for controlling the dissipation of electrical energy productive of such discharges. The present invention is an improvement in apparatus of the type disclosed in my copending application Serial No. 164,320, filed September 16, 1937, for Induction heat treating apparatus. In that application there is disclosed an apparatus in which an induction heating element in the form of a coil having a magnetic core element is arranged to be inserted in a hollow work-piece of magnetic material, for example, within the inner cylindrical portion of an iron wheel hub, engine cylinder or the like, the work-piece acting to complete, or form a substantial part of a magnetic circuit conducting element of high permeability for the heating coil. A pair of relatively short circuit conductor elements connect the heating coil to a source of high frequency current for energization thereby, the circuit formed by the coil and the said conductors being tuned or adjusted by connection therewith of a suitable condenser or condensers for power-factor correction of the circuit under the electrical conditions which exist when the heating coil is in operative relation with the work-piece. In the normal operation of such a machine upon work-pieces substantially identical and to which the machine is adjusted to maximum efficiency, the operations are found to be uniform with substantially no undesirable electrical effects such as undue arcing, insulation breakdown or the like. However, occasionally, due to some accidental variation in the character of the work-piece, severe electrical disturbances are produced which manifest themselves in resistance breakdown or arcing over between insulated portions of the circuit, particularly near the terminals of the inductive heating element and at points along the conducting elements connecting the heating coil or work circuit with the source of current supply.

In practice, it is noted that such points of disruptive discharge occur at different places at different times.

While the causes of such phenomena are not definitely understood at present, at least not sufficiently to attempt to explain them at this time, it has been observed that the phenomena usually occur when an attempt is made to operate upon the defective work-piece, for example one that varies widely in quality of material, internal

structure or even shape and size, from that of the standard type of work-pieces to which the machine is adjusted, or pieces that have a tendency to crack during treatment resulting in a flashing over at the cracked portion, and it is believed that such imperfections in the work-piece bring about sudden electrical changes in the circuit of the apparatus, for example a sudden reduction or other variation in the permeability of the magnetic circuit of the heating coil or other sudden electrical charges thus producing transient currents in the circuit of the apparatus, perhaps of extremely high frequency, resulting in the establishment of an excessively high potential at certain points with nodes of substantially zero potential at other points such as would be produced by a high frequency stationary voltage wave in the circuit of the apparatus, the location of such crests and nodes varying according to the length of such stationary wave. This would account for the variation in location of the flash over point at different times.

The main object of the invention is, therefore, to provide means for preventing the occurrence of such disruptive discharges at undesirable points such as through the insulation of the machine and to effect dissipation of the electrical energy producing such discharges without injury to the insulation or other parts of the apparatus.

This object of the invention is attained by the provision at various points in the circuit of high break-down-voltage, resistance devices adjusted to have a break-down voltage less than that of the insulating material separating the conducting elements and spaced at intervals so as to insure the presence of one of them at or near the point of excessively high potential occurring at different times and in different places. Thus while one of such discharge devices may be ineffective because situated at or near a node of zero potential, some one of the others would be situated sufficiently close to the high voltage point to permit controlled disruptive discharge through the high resistance device in preference to a discharge through the insulation.

The above and other important features of the invention may be more clearly understood from a perusal of the following specification and the drawing accompanying the same.

In the drawing:

Fig. 1 is a fragmentary view partly in section showing portions of an induction heating machine with the invention applied thereto.

Fig. 2 is an enlarged fragmentary view show-

ing one form of the high resistance discharge device and its connection to the apparatus.

Fig. 3 is an enlarged fragmentary sectional view showing other forms of the discharge device as applied to a pair of concentric conductors and the relation of the conductors to the heating coil and source of current.

Referring to the drawing in detail, the portion of the heat treating apparatus to which the invention is applied comprises an inductive heating coil element 10 carried by a pair of circuit conductor elements 11 and 12 which connect the terminals of the heating coil to a suitable source of high frequency current which may be the secondary coil 13 of a transformer supplied from a high frequency generator 14. The conductor elements 11 and 12 are insulated from each other by an intervening sleeve 15 of insulating material. For the sake of compactness such insulation is necessarily relatively thin thus producing an appreciable capacity coupling between the conducting elements but which is sufficiently small, relative to the frequency used, not to interfere with the proper operation of the apparatus.

As shown diagrammatically in Fig. 3 the heating coil 10 is provided with a magnetic core element 16 forming part of a magnetic circuit for the coil, which magnetic circuit is completed by the work-piece 17 of a permeability which is high relative to that of air. The apparatus elements thus shown, together with the work-piece 17 forming a part of a low reluctance magnetic circuit for the heating coil 10, constitute an electrical power transmission system with an inductive-load work circuit. The electrical system thus including the work-piece 17 is corrected for optimum power-factor by the condenser 18 connected across the circuit near the source 13. Once established such adjustment may remain unchanged so long as the interchangeable work pieces remain substantially identical in certain characteristics such as quality of material, internal structure, shape, size, etc.

Inasmuch as the tendency to disruptive discharge around or through the insulation occurs at different places at different times, the protective disruptive discharge devices are placed at different points along the circuit to insure the presence of one of them at or near a high potential zone. For convenience and expediency in installation, such devices are made to vary in form according to the place where they are to be used. However, each of the protective devices consists in general of a high resistance element 19 and an air gap 20 connected in series between the two portions of the apparatus near which undue high voltage may occur, and adjusted as to its electrical constants to form a high break-down-voltage resistance device. As indicated in Figures 1 and 2, one such discharge device 21 is shown connected between the lower extremities of the conductor elements 11 and 12 near the terminals of the heating coil 10. The discharge device 21 comprises a short cylindrical casing 22 of insulating material secured to the lower end of the inner conductor element 11 by the metallic screw 23. Within the casing is a leaf spring element 24 bearing at its central portion against the head of the screw 23 and at its end portions against contact plate 25 against which bears a resistor element 19 of "Thyrite," the resistance material described in the patent of McEachron No. 1,822,742, dated September 8, 1931, or other suitable resistance material of similar character.

istics, between which and a second metallic disc 26 is placed a mica disc 27 having an aperture 28 therein providing an air gap 20 between the "Thyrite" resistor disc 19 and the outer metal disc 26. A metallic cover 29 screwed onto the lower outer portion of the casing 22 holds the outer disc 26 against the mica disc 27 through a leaf spring element 30 which also establishes electrical connection between the disc 26 and the metal cover 29. A jumper-strip 31 electrically connects the cover 29 with the lower extremity of the outer concentric conductor element 12. Thus the cover element 29 which is electrically connected to the outer conducting element 12 is insulated from the lower extremity of the inner conducting element 11 by the base of the insulating box 22 but provides for a disruptive discharge between the lower extremities of the elements 12 and 11 by way of jumper-strip 31, metallic cover element 29, spring 30, metallic disc 26, air gap 20, "Thyrite" resistor 19, metallic disc 25, spring 24, and through attaching screw 23 to conductor element 11.

For insertion between the concentric conductors the discharge device may take the form shown at 32 in Figures 1 and 3, in which form it consists simply of an annular band 33 of "Thyrite" or like resistor material placed around the inner conductor 11 and of less wall thickness than the insulating sleeve 15 so as to provide an air gap 34 between the resistor element 33 and one of the concentric conductor elements. In the form illustrated the ring of resistance material 33 is fitted in contact with the inner conductor element 11 and spaced from the outer conductor to form the air gap 34. However, it is to be understood that the resistance element may have an outside diameter sufficient to place it in contact with the outer conductor 12, and an inside diameter less than the outer diameter of the inner conductor so as to produce an air gap at the outer surface of the inner conductor.

At other places along the circuit formed by conductors 11 and 12, where desirable or convenient, the discharge device may take the form of that shown at 35 in Figure 3 where it consists simply of a disc or plate 36 of resistance material such as "Thyrite" held in electrical contact with the inner conductor 11 by a metallic plug element 37 with an intervening perforated mica disc 38 providing an air gap 39 between the plug 37 and resistance element, the plug 37 being threaded into an opening 40 in the outer conducting element 12, establishing electrical contact therewith. Thus at this point the outer conductor 12 is maintained insulated from the inner conductor 11 while a disruptive discharge path is provided between the two conductors by way of the conducting plug 37, air gap 39 and resistance element 36.

The discharge elements may take various other forms according to what form might be most convenient for the particular location chosen, the essential feature being that they comprise a resistance element of "Thyrite" or similar substance and an air gap connected in series between the conductor elements and adjusted as to their electrical constants to a break-down voltage lower than that of the insulating material in the vicinity of the discharge device.

It will of course be understood that the air gap, which may be ".004", is sufficient to provide a broken circuit for any voltage of the order of standard voltages such as 110, 220, etc., but quickly breaks down upon sudden abnormal volt-

age rises. The "Thyrite" thereafter has the characteristic of rapidly lowering its resistance as higher and higher voltages are applied, so that with the high transient voltages, it becomes a virtual short circuit, for as long as the high voltage exists, but immediately becoming restored as soon as that voltage disappears. It will also be understood that the air gap can be omitted, since leakage through the "Thyrite" would be almost negligible at ordinary voltages. While a plurality of discharge devices have been shown in various positions, if the point of usual occurrence of discharge of the high voltage appears to be in a single position, a single device if placed in that position will be found to suffice. For example, a single device 21 such as that shown in Fig. 2, when properly located, may afford all the protection necessary.

On the other hand by so placing several of the discharge devices at different points in the circuit the positioning of one of them at or near a point of high voltage stress is assured.

While I have thus shown and described a specific embodiment of my invention for the sake of disclosure, it is to be understood that the invention is not limited to such specific embodiment but contemplates all such variants and modifications thereof as fall fairly within the scope of the appended claims.

What I claim is:

1. In a high power induction heating apparatus, a supporting and conducting arbor having concentric conductors spaced from one another, a high frequency heat treating coil secured to one end of the arbor and electrically connected to the conductors, and a protective energy consuming shunt device connected across said concentric conductors at said one end, said device comprising a resistance and an air gap in series, said resistance being of non-linear characteristics such as "Thyrite."
- 5 2. In a high power induction heating apparatus, a supporting and conducting arbor having concentric conductors spaced from one another by a sleeve of insulating material, a high frequency heat-treating coil secured to one end of the arbor and electrically connected to the conductors, said sleeve of insulating material being interrupted for a short distance along its length to form an annular gap, and an annular sleeve of resistance material being positioned in said gap and of a thickness less than the insulating material to provide a short air gap between the concentric conductors, said resistance material having non-linear resistance characteristics such as "Thyrite."
